UNITED STATES PATENT OFFICE

HERBERT F. DYCK, OF NESS CITY, KANSAS

MEASURING BOTTLE

Application filed March 6, 1930. Serial No. 433,772.

This invention relates to a measuring bottle designed primarily for use in carrying and measuring medicines, but it is to be understood that a bottle in accordance with this invention may be used for any purpose for which the same is found to be applicable.

The principal object of the invention is to provide, in a manner hereinafter set forth, a bottle of the class above referred to by 10 means of which varying quantities of liquid of accurate proportions may be measured and discharged.

A further object of the invention is to provide a measuring bottle for the purpose aforesaid which is designed in a manner to provide for the transfer of a portion of the contents thereof from the storage compartment to the discharge compartment without bringing the transferred portion into contact with 15 the stopper for the discharge compartment, thereby guarding the contents of the bottle against contamination by the stopper, and protecting the hands from becoming soiled by the contents when the stopper is removed, 20 and further providing for the removal of the stopper, if desired, before any portion of the contents is transferred to the discharge compartment.

A further object of the invention is to provide a bottle of the class aforesaid, which is constructed in a manner to permit a quantity being transferred from the storage compartment to the discharge compartment and discharged from the latter without the inadvertent transfer of any additional amount, 25 so long as a quantity equal to the transferred quantity remains in the storage compartment.

A further object of the invention is to provide a bottle of the class aforesaid which is sanitary and efficient in use, strong and durable in construction, inexpensive to manufacture, and which may be readily refilled after the contents thereof have been emptied.

With the foregoing and other objects in view, the invention consists of the novel construction, combination and arrangement of parts as hereinafter more particularly described, and as illustrated in the accompanying drawings wherein is shown an embodi-

ment of the invention, but it is to be understood that the description and drawings are to be taken as illustrative, and that the invention is intended to be limited only by the scope of the claims hereunto appended.

In the accompanying drawings in which like numerals are employed to designate like parts throughout the several views:—

Figure 1 is a top plan of a measuring bottle in accordance with this invention, showing 60 the same in position to effect the transfer of a portion of the contents from the storage compartment to the discharge compartment.

Figure 2 is a longitudinal section of the bottle showing the same in position to prevent any interchange of contents between the compartments and further to prevent any discharge from the discharge compartment.

Figure 3 is an end elevation showing the 70 relative positions of the storage and discharge compartments.

Figure 4 is a section taken on the line 4—4 of Figure 1.

Figure 5 is a section taken on the line 5—5 75 of Figure 2.

Figure 6 is a sectional elevation of the bottle showing the same in position for discharging the contents of the discharge compartment.

Referring to the drawings in detail, the 80 numeral 1 indicates the body portion of my improved bottle, such body portion being of oblong shape in cross section and merging at one end into a breast portion 2 which terminates in a neck portion 3 extending at an angle to the longitudinal plane of the body portion, as well as to the transverse planes through the major and minor dimensions thereof.

Substantially at the line of mergence between the body and breast portions 1 and 2 is a partition 4 which divides the interior of the bottle into a storage compartment 5 and a discharge compartment 6. A suitable filler neck 7 having a closure cap 8 is provided on 90 the body portion 1 whereby the storage compartment 5 may have any suitable ingredient, such as a liquid medicine, introduced therein. The partition 4 is of elongated 95 shape to conform with the cross sectional 100

shape of the body portion 1, and formed in the partition, adjacent one end thereof, is a relatively small opening 9 to provide a liquid passageway between the compartments 5 and 6, and a relatively large opening 10 to provide an air passageway therebetween.

The openings 9 and 10 are so disposed relative to each other that when the body portion 1 is positioned with its lesser cross sectional dimension disposed vertically, the 10 openings will be in vertical alinement, and when the body portion 1 is positioned with its greater cross sectional dimension disposed vertically, the openings will be in horizontal alinement. The openings 9 and 10 are further disposed relative to each other and to the neck 3 so that when the body portion 1 is disposed in measuring position, the opening 15 10 will be directly above the opening 9 as shown in Figure 4, and when the body portion 1 is disposed in position to prevent any interchange of the contents of the compartments 5 and 6, the openings will be at substantially the same level and further will be 20 oppositely disposed with respect to the neck 25 3, as shown in Figure 5.

In Figure 2, there is illustrated at 11 the liquid level of a full quantity or dose which may be contained within the discharge compartment 6 without the use of a stopper for the neck 3, or without coming in contact with a stopper, such as 12, in the event that a stopper is employed. The contents of the breast portion 2 and neck portion 3 as shown in Figure 2 are equal to the entire volume of the neck portion 3 with the stopper 12 in position. There is also illustrated in Figure 2, at 13, the level of a quantity of liquid within the storage compartment 5 equal to that contained within the discharge compartment 6. 30 It will be noted that such a quantity within the storage compartment is sufficient to effectively seal the openings 9 and 10 against the atmosphere. In Figure 6, the bottle is shown 35 tilted to discharge position, and in such position, the level of the liquid remaining in the storage compartment 5 is indicated at 14. It is to be noted that the level as shown at 14 is materially above the level of the openings 9 and 10, which illustrates that a measured 40 quantity materially less than the full neck quantity above mentioned, may be retained within the compartment 6, with the openings 9 and 10 effectively sealed by a corresponding 45 quantity within the compartment 5.

When it is desired to transfer a portion of the contents of the compartment 5 to the compartment 6, the bottle is positioned in the manner illustrated in Figures 1 and 4, in 50 which position air enters the compartment 5 through the opening 10 and forces liquid through the opening 9 into the compartment 6. When the desired amount has passed into the compartment 6, the bottle is rotated axially 55 90° to assume the position illustrated in

Figures 2 and 5, in which position the openings 9 and 10 are closed by the liquid remaining within the compartment 5 and any further interchange of liquid between the compartments 5 and 6 is prevented. Owing to 70 the angular relation of the neck portion 3 to the body portion 1, the neck portion is disposed at an upward inclination from the body portion when the latter is in measuring position and when axially rotated 90° therefrom 75 to pre-pouring position. When it is desired to discharge the contents of the compartment 6, the bottle is tilted to the position illustrated in Figure 6.

The openings 9 and 10 remain closed during 80 the tilting operation, thereby preventing any further quantity of liquid being passed to the compartment 6 during the emptying operation of the latter. Preferably the outer walls 85 of the breast and neck portions 2 and 3 respectively will be calibrated as indicated at 15 and 16, and the neck will be provided with a pouring lip as indicated at 17.

It is thought that the many advantages of a measuring bottle in accordance with this invention will be readily apparent, and although the preferred embodiment of the invention is as illustrated and described, it is to be understood that changes in the details of construction may be resorted to, so long 95 as such changes fall within the scope of the invention as defined in the appended claims.

What I claim is:

1. A measuring bottle comprising, a body portion, a breast portion at one end of the 100 body portion, a neck portion extending from the breast portion, and a partition substantially at the line of joinder between the body and breast portions, said partition having a pair of openings arranged in different horizontal planes when the body portion is disposed in one position, said openings being arranged in the same horizontal plane when the body portion is rotated axially substantially 90° from said position, said neck portion 105 extending at an upward inclination from the body portion when the latter is in said position and when rotated axially 90° therefrom in one direction.

2. A measuring bottle comprising, a body 115 portion, a breast portion at one end of the body portion, a neck portion extending from the breast portion, and a partition substantially at the line of joinder between the body and breast portions, said partition having a 120 pair of openings arranged in different horizontal planes when the body portion is disposed in measuring position, said openings being arranged in the same horizontal plane when the body portion is rotated axially substantially 90° to pre-pouring position, said neck portion extending at an upward inclination from the body portion when the latter is in both of said positions and when being rotated 125 from measuring position to pre-pour- 130

- ing position, one of said openings being of materially greater diameter than the other.
3. A measuring bottle comprising, a body portion, a breast portion at one end of the body portion, a neck portion extending from the breast portion, and a partition substantially at the line of joinder between the body and breast portions, said partition having a pair of openings arranged in different horizontal planes when the body portion is disposed in one position, said openings being arranged in the same horizontal plane when the body portion is rotated axially substantially 90° from said position, said neck portion 70 extending at an angle to the horizontal and vertical planes of the body portion when the latter is in the said position, said body portion being of elongated cross sectional shape, said partition being of elongated 75 shape to conform with the cross sectional shape of the body portion, said openings being arranged adjacent one end of the partition.
4. A measuring bottle comprising, a body portion rectangular in cross section, a breast portion at one end of the body portion, a neck portion extending from the breast portion in angular relation to the longitudinal plane of the body portion and to the transverse planes 80 through the major and minor dimensions thereof, and a partition substantially at the line of joinder between the body and breast portions, said partition having a pair of openings arranged in different horizontal planes when the body portion is disposed in one position, said openings being arranged in the same horizontal plane when the body portion is rotated axially substantially 90° from said position, said breast and neck portions 85 being calibrated, said body portion having a filler neck and cap.
5. A measuring bottle comprising, a body portion, a breast portion at one end of the body portion, a neck portion extending from the breast portion, and a partition disposed substantially at the line of joinder between the breast and neck portions, said partition having a pair of openings arranged in different horizontal planes when the body portion 90 is disposed in one position, one of said openings being adjacent the top of the body portion and the other of said openings being adjacent the bottom of the body portion when the latter is in said position, said openings being arranged in the same horizontal plane adjacent the bottom of the body portion when the latter is rotated axially substantially 90° in one direction from the said position, said body portion being of elongated cross sectional shape, said partition being of elongated shape to conform with the cross sectional shape of the body portion, said openings being arranged adjacent one end of the partition.
6. A measuring comprising, a body portion, a breast portion at one end of the body portion, a neck portion extending from the breast portion, and a partition disposed substantially at the line of joinder between the breast and neck portions, said partition having a pair of openings arranged in different 100 horizontal planes when the body portion is disposed in one position, one of said openings being adjacent the top of the body portion and the other of said openings being adjacent the bottom of the body portion when the latter is in the said position, said openings being arranged in the same horizontal plane adjacent the bottom of the body portion when the latter is rotated axially substantially 90° in one direction from the said position, said neck portion extending at an angle to the horizontal and vertical planes of the body portion when the latter is in the said position and when the body portion is rotated axially 105 110 115 120 125 130 90° therefrom.
7. A measuring bottle comprising, a body portion, a breast portion at one end of the body portion, a neck portion extending from the breast portion, and a partition disposed substantially at the line of joinder between the breast and neck portions, said partition having a pair of openings arranged in different horizontal planes when the body portion is disposed in one position, one of said openings being adjacent the top of the body portion and the other of said openings being adjacent the bottom of the body portion when the latter is in said position, said openings being arranged in the same horizontal plane adjacent the bottom of the body portion when the latter is rotated axially substantially 90° in one direction from the said position, one of said openings being of materially greater diameter than the other.
8. A measuring bottle comprising, a body portion, a breast portion at one end of the body portion, a neck portion extending from the breast portion, and a partition disposed substantially at the line of joinder between the breast and neck portions, said partition having a pair of openings arranged in different horizontal planes when the body portion is disposed in one position, one of said openings being adjacent the top of the body portion and the other of said openings being adjacent the bottom of the body portion when the latter is in said position, said openings being arranged in the same horizontal plane adjacent the bottom of the body portion when the latter is rotated axially substantially 90° in one direction from the said position, said body portion being of elongated cross sectional shape, said partition being of elongated shape to conform with the cross sectional shape of the body portion, said openings being arranged adjacent one end of the partition.

In testimony whereof, I affix my signature hereto.

HERBERT F. DYCK. 125
